UNITED STATES PATENT OFFICE.

WARREN D. HOUSE, OF KANSAS CITY, MISSOURI, ASSIGNOR TO THE HOUSE
IMPROVED TELEPHONE COMPANY, OF PHILADELPHIA, PENNSYLVANIA.

TELEPHONE.

SPECIFICATION forming part of Letters Patent No. 380,437, dated April 3, 1888.

Application filed March 1, 1887. Serial No. 229,363. (No model.)

To all whom it may concern:

Be it known that I, WARREN D. HOUSE, a citizen of the United States, residing at Kansas City, in the county of Jackson and State of Missouri, have invented certain new and useful Improvements in Telephones; and I do hereby declare the following to be a full, clear, and exact description of the invention, such as will enable others skilled in the art to which it appertains to make and use the same.

In Letters Patent of the United States granted to me March 1, 1887, and numbered 358,812, I have described an apparatus for telephonic receiving, wherein the transmitting-currents corresponding to the sound-waves were caused to set into molecular vibration of like character a body of vibratory electrolytic material in contact with a moving electrode, thereby reproducing the original sounds.

The object of my present invention is to furnish a modified construction of the instruments therein described, of simple, economical, and durable character, and which will readily maintain its efficiency throughout a long period of use.

To this end my invention consists in the arrangement illustrated in the accompanying drawings, wherein—

Figure 1 represents a side elevation, partly in section, of one form of my invention. Fig. 2 represents a sectional view taken upon the line $x\ x$ of Fig. 1. Fig. 3 represents a side elevation and partial section of a modification of the invention. Fig. 4 represents a section taken upon the line $y\ y$ of Fig. 3. Fig. 5 represents a side elevation and partial section of still another modification of the invention; and Fig. 6 represents a rear elevation thereof, taken on the line $z\ z$ of Fig. 5.

Similar letters of reference indicate similar parts throughout the several views.

Referring to Figs. 1 and 2, the instrument as therein illustrated consists of a box or casing, A, provided with a suitable aperture, a , across which is secured conducting-body C, preferably of carbon. To the inner surface of this conducting-body C is electrically connected a body, D, of vibratory electrolytic material of the character described in my patent above referred to—as, for instance, a body of plaster-

of-paris compressed to give it stability and saturated with an aqueous solution—said body being preferably provided with a removable cover, E, of the same material, and inclosing an electrolytic solution, F, used to maintain saturation of the main body D and cover E. Upon the exterior surface of the cover E rests the axially-revolving electrode G, mounted upon a rotary shaft, H, supported in suitable bearings, as I I². The shaft H may receive its motion from any suitable actuating mechanism driven from some convenient source of power. In the drawings I have shown for this purpose a crank-shaft, J, with handle K, said shaft being provided with a fixed pinion meshing with the teeth of a wheel, L, fixed upon a sleeve, M, said sleeve being adapted to be locked to the shaft H, so as to revolve therewith, by means of a set-screw, f, or its equivalent, having longitudinal play within a groove, f'. At its inner end the shaft H is encircled by the coiled spring N, bearing at one end against the arm I² and at its other end against the sliding collar Q, which rests against the adjusting-nut R traveling in a screw-thread upon the shaft. By means of this device the electrode G is forced against the electrolytic body E with a pressure that may be regulated at will by means of the adjusting-nut R.

The operation of this portion of my invention will be apparent, the instrument being connected up in accordance with the conditions prescribed in my aforesaid patent. During the passage of the transmitting currents the shaft H is revolved, thereby causing the electrode G, which is held with pressure against the vibratory electrolytic material, to revolve with friction against the surface of the latter. Molecular electrolytic vibrations, in character corresponding to the received currents, are set up, and, being imparted to the air, reproduce the original sounds. The large surface of contact between the electrolytic body and the axially-revolving opposite electrode, as shown in Figs. 1 and 2, insures the production of the requisite state of polarization when the electrolytic body is of high resistance.

When the electrolytic body is of comparatively low resistance, I find it desirable to have

a lesser portion of its surface in contact with the moving electrode. Thus, as illustrated in Figs. 3, 5, and 6, this arrangement may be readily attained by having the axially-revolving electrode move in a plane normal to the surface of the electrolytic body, its edge moving in contact with said surface.

It is obvious that the dimensions of the axially-revolving electrode in either instance may be varied to correspond to the particular requirements of use.

In Figs. 3, 5, and 6 I have illustrated another means of rotating the axially-revolving electrode G, said figures exhibiting the same arrangement of parts therefor.

The axially-revolving electrode G is affixed to a shaft, H', mounted in suitable standards, as I³ I⁴, said shaft being provided with the fixed cog-wheel L', engaging with a pinion 25 fixed on a shaft, J'. The shaft J' has affixed thereto a cog-wheel, K', intermeshing with a worm formed upon the shaft M', constituting a prolongation of the armature-shaft of the electric motor T, attached to the bottom of 25 the casing, and which may be of any adequate construction.

In the form of my invention shown in Figs. 3 and 4 the electrolytic body D', with its carbon facing C', is held in an annular hollow-rim casing P, filled with a saturating solution, F', having a feed-opening closed by a screw-plug, b, the whole constituting a saturated diaphragm supported at its edges. It is apparent that the form of the diaphragm may be 35 varied within wide limits.

The diaphragm-support S is hinged, as at c, to the casing A', and at its upper end is fastened a spring, d, against which bears a setscrew, e, whereby the requisite degree of 40 pressure between the diaphragm and the electrode G may be secured. The mouth-piece V, having an opening, a', is hinged, as at c', to the casing A', and has an internally-screw-threaded aperture, within which engages the 45 externally-screw-threaded adjusting-screw e. At the upper edge of the mouth-piece V is a spring-catch, g, engaging with a spring-catch, h, attached to the inner wall of the casing A', said engagement being releasable at will by 50 means of the push-pin i.

In the form of my invention shown in Figs. 5 and 6 the parts lettered as in Figs. 3 and 4 correspond to similarly designated parts in said latter figures.

55 In this modification the diaphragm is composed of rectangular plates D² and C² of electrolytic material and carbon, respectively, said plates fastened to the support S in any suitable manner. The saturating solution F² is contained 60 in a receptacle, P', fastened to the upper portion

of the compound diaphragm, as shown. Absorption of the saturating solution is facilitated by conducting it to various parts of the diaphragm by means of grooves or channels j intermediate between the plates D² and C², the 65 said grooves or channels being closed at one end.

The operation of the modifications shown in Figs. 3 and 4 and in Figs. 5 and 6 is similar to that already described with reference to Figs. 1 and 2.

It will be understood that any of the three forms described may be employed also as a transmitter when connected up with a receiver in the ordinary manner employed in variable 75 contact-transmitters, the adjustment of the circuit-controlling electrodes (which consists of the electrolytic body and its opposing electrode) being regulated by means of the spring-pressing devices shown in each of the figures. 80 When operated either as transmitters or receivers, the resistance of the polarizing-battery should preferably be approximately that of the electrolytic body.

It will be noted that in all three forms of my 85 invention the same portion of the electrolytic body is constantly in contact with the opposite electrode. This arrangement insures an even and constant adjustment of the instrument, the continuance of use increasing the intimacy of contact between the opposing surfaces.

I claim—

1. In a telephone, the combination, with a body of vibratory electrolytic material, of an 95 opposite electrode and means for moving the two relatively to each other, the same portion of the electrolytic body being constantly in contact with said electrode, substantially as described.

2. A telephone provided with a body of vibratory electrolytic material and an opposite axially-revolving-plate electrode in contact therewith, substantially as described.

3. A telephone provided with a body of vibratory electrolytic material, and an opposite axially-revolving-plate electrode having its edge in contact with said electrolytic body, substantially as described.

4. A telephone provided with a diaphragm 110 of vibratory electrolytic material having a facing of conducting material and a rim-casing containing a saturating solution, substantially as described.

In testimony whereof I affix my signature in 115 presence of two witnesses.

WARREN D. HOUSE.
